HANGER FOR SLACKS OR SIMILAR ARTICLE

Herb Coon, Kings Point, N.Y., assignor to Red Wing Products, New Hyde Park, N.Y., a partnership

Application September 10, 1958, Serial No. 52,595

Term of patent 14 years

(Cl. D80—8)

I claim:

The ornamental design for a hanger for slacks or similar article, substantially as shown.
